UNITED STATES PATENT OFFICE.

CHARLES F. CLAWSON, OF MOUNT PLEASANT, IOWA.

COMBINATION TIE-PLATE AND TRACK-ANCHOR.

1,050,613.

Specification of Letters Patent. Patented Jan. 14, 1913.

Application filed January 4, 1912. Serial No. 868,411.

To all whom it may concern:

Be it known that I, CHARLES F. CLAWSON, a citizen of the United States, residing at Mount Pleasant, in the county of Henry and 5 State of Iowa, have invented certain new and useful Improvements in Combination Tie-Plates and Track-Anchors; and I do declare the following to be a full, clear, and exact description of the invention, such as 10 will enable others skilled in the art to which it appertains to make and use the same.

This invention relates to improvements in combination tie plates or chairs and anchors 15 for railway rails.

One object of the invention is to provide a tie plate or chair for railway rails adapted to be engaged with two or more ties to form seats for the rail and to hold the latter 20 in position on the ties.

Another object is to provide a tie plate which will be strong, durable and inexpensive in construction, efficient and reliable in operation and well adapted to the purpose 25 for which it is designed.

With these and other objects in view the invention consists of certain novel features of construction, and the combination and arrangement of parts as will be more fully 30 described and claimed.

In the accompanying drawings; Figure 1 is a plan view of my improved tie plate; Fig. 2 is a side view thereof; Fig. 3 is an end view showing the rail in dotted lines; 35 Fig. 4 is a cross sectional view on the line 4-4 of Fig. 1. Fig. 5 is a side view of a modified form of my improved tie plate.

Referring more particularly to the drawings, 1 denotes my improved tie plate which 40 comprises end tie members or seats 2 which are spaced a suitable distance apart and are connected together by an integral web or neck 3 which is of considerably less width than the seats or members 2 and which has 45 its edges formed on a gradually increasing curve from the center thereof toward the inner ends of the seats 2, said curved edges of the neck merging into the edges of the inner ends of the seats as shown. When 50 thus arranged the seats 2 will be spaced apart at a suitable distance for engaging two ties.

On the upper sides of the seats 2 and 55 spaced a suitable distance apart are upwardly projecting longitudinally disposed rail engaging ribs or flanges 4, which are

adapted to engage the outer edges of the base flanges of the rail when engaged with the seats as clearly shown in Fig. 3 of the drawings. In the members or seats 2 and 60 intersecting the ribs 4 are spike holes 5 through which spikes are driven to fasten the plates to the ties and to fasten the rails to the plates. Formed on the lower side of the members or seats 2 are longitudinally 65 disposed V-shaped ribs 6, which when the plates are engaged with the ties, bite into the upper sides of the latter and thus securely hold the plates from slipping laterally on the ties.

Formed on the lower sides of the inner ends of the seats 2 and adjacent to the outer ends of the neck 3 are depending stop lugs 7, said lugs being disposed at right angles to the lower sides of the seats 2 and adapted 75 to engage or fit against the adjacent sides of the ties on which the seats 2 rest, said lugs holding the plate against longitudinal movement in either direction. The plates 7 are firmly braced by rib 13 having webs 8 80 formed integral therewith and with the under side of the neck 3 as shown. The neck 3 is preferably slightly concaved or curved longitudinally on its upper side and has formed on the lower side thereof 85 longitudinally disposed bracing ribs or flanges 9 which preferably follow the contour of the side edges of the neck and have their ends joining or formed integral with the stop lugs 7 as shown. As clearly shown, 90 the reduced centrally disposed neck 3 of the anchor is arched and extends below the tie members or sides 2, and said arched portion is properly strengthened by a longitudinal rib 13 terminating in depending ends 7 95 which contact with the ties, whereby the sides are readily connected and braced with the rail bearing only upon the sides and out of contact with the arched neck.

In applying the plates they are engaged 100 with two ties which are arranged a suitable distance apart for this purpose and when so applied the stop lugs 7 will engage the contiguous surfaces of the ties and thus hold the plates against longitudinal movement 105 and will also relieve the spikes of all strain due to the tendency of the plate to move in one direction or the other. When the plates are spiked down onto the ties the ribs 6 will be forced into the upper surface of the ties 110 and will thus effectually hold the plates against lateral movement and will relieve

the spikes of strain in this direction. The engagement of the ribs 6 with the ties forms a positive means for preventing the rails from spreading after the latter and the plates have been spiked to the ties.

In Fig. 5 of the drawings is shown a slightly modified form of my improved tie plate 10. In the latter form of plate the tie engaging lugs 7 are omitted and the plate is 10 secured to the ties and held in position by spikes and the tie engaging ribs 11 on the under side of the seats or tie engaging members 12 of the plate. With the exception of the tie engaging lugs 7, the plate 10 is constructed 15 in the same manner as the preferred form of the plate and a further description of the modified form is not thought to be necessary.

From the foregoing description taken in connection with the accompanying drawings, the construction and operation of the invention will be readily understood without requiring a more extended explanation.

Various changes in the form, proportion and the minor details of construction may 25 be resorted to without departing from the principle or sacrificing any of the advantages of the invention as claimed.

Having thus described my invention, what I claim is;

30 A device of the character set forth com-

prising tie engaging plates of rectangular shape adapted to rest on the tops of two adjacent ties, parallel longitudinally extending flanges formed on the upper side of said plates, the latter being formed with 35 spike holes cut through said rail engaging flanges, V-shaped tie engaging ribs formed on the lower sides of said plates parallel with the rail engaging flanges and adapted to bite into the upper surfaces of the ties, a 40 reduced neck formed integral with the plates, longitudinal bracing flanges formed on the bottom of said reduced neck at its side edges, depending stop lugs formed integral with said bracing flanges and at the 45 junction of said neck and plates, said lugs engaging the opposite side faces of two ties, and a longitudinal bracing rib formed centrally on the bottom of the reduced neck, said bracing rib being formed with enlarged 50 depending webs integrally united with said lugs to brace and reinforce the same.

In testimony whereof I have hereunto set my hand in presence of two subscribing witnesses.

CHARLES F. CLAWSON.
